Inventor
Edwin W. Parker
by Alban Andrew, his Atty.

UNITED STATES PATENT OFFICE.

EDWIN W. PARKER, OF WALTHAM, ASSIGNOR OF ONE-HALF TO THE
NONANTUM WORSTED COMPANY, OF NEWTON, MASSACHUSETTS.

VAPORIZER.

SPECIFICATION forming part of Letters Patent No. 428,054, dated May 13, 1890.

Application filed March 10, 1890. Serial No. 343,284. (No model.)

To all whom it may concern:

Be it known that I, EDWIN W. PARKER, a citizen of the United States, and a resident of Waltham, in the county of Middlesex and 5 State of Massachusetts, have invented new and useful Improvements in Vaporizers, of which the following, taken in connection with the accompanying drawings, is a specification.

This invention relates to improvements in 10 vaporizers for the purpose of moistening the air in mills, factories, dwellings, &c., and it is carried out as follows, reference being had to the accompanying drawings, where—

Figure 1 represents a perspective view of 15 the improved apparatus. Fig. 2 represents a central longitudinal section of the same. Fig. 3 represents a cross-section on the line X X shown in Fig. 2. Fig. 4 represents a detail perspective and cross-section of the pivoted 20 dash-plate, and Fig. 5 represents a detail perspective view of the longitudinally-grooved valve.

Similar letters refer to similar parts wherever they occur on the different parts of the 25 drawings.

a represents a water-supply pipe leading from any suitable source of water-pressure, such pipe being provided with a suitable cock, valve, or cut-off *b*, as is usual in devices of 30 this kind.

a' is a bend or elbow secured to the upper part of the pipe *a*, as shown in Figs. 1 and 2. To said elbow is secured one end of the delivery-pipe *c*, which pipe has its forward end 35 provided with an internal tapering valve-seat *c'*, against which is made to rest the tapering valve-plug *d*, as shown in Fig. 2. The said valve-plug is provided with fine longitudinal grooves or scratches *d' d'*, through which the 40 water is forced out from the delivery-pipe *c* in very fine streams against the dash plate or breaker, hereinafter to be described.

The valve *d* is held against its seat by means 45 of a lever *e*, pivoted at *e'* to the end of the pipe *c*, said lever being held with proper pressure against the outer end of said valve by means of a spring *f*, having one of its ends secured to a hook or projection *c''* on the pipe *c*, and its other end adapted to rest in one of 50 the notches *e'' e'' e''* on said lever, as shown in Figs. 1 and 2. I make a number of such

notches *e''* on the said lever *e*, for the purpose of attaching the spring *f* to the said lever at various distances from its fulcrum, according to the pressure in the delivery-pipe *c*, so as to 55 hold the valve *d* against its seat at all times, except when flushing or cleaning its grooves from obstructions or impurities, as will hereinafter be described.

To ears or brackets *g g*, secured to the outer 60 end of the delivery-pipe *c*, is pivoted at *g' g'* the dash plate or breaker *G*, having inclined faces *G' G'*, against which the fine spray or vapor forced out through the longitudinal grooves or scratches *d' d'* strikes, causing it 65 to be deflected upward and outward and intimately mixed with the air in the room, thereby moistening it, for the purpose set forth.

G'' is an arm or lever preferably secured in a suitable manner to the dash-plate *G* or 70 one of its pivots, which may be manipulated either by hand or by means of a suitable rod for the purpose of adjusting the position and inclination of the said dash-plate, according to the direction in which the moisture is to be 75 directed into the room.

Below the pipe *c* and dash-plate *G* is located the inclined conductor *H*, for automatically conveying any liquid dripping from said pipe and dash-plate to the drain-pipe *h*, that is attached to the lower end of said conductor *H*, 80 as shown in Figs. 1 and 2.

If the grooves or scratches *d' d'* in the tapering valve *d* should become clogged up, it is only necessary to take hold of the lever *e* 85 and swing it slightly on its fulcrum in the direction of arrow shown in Fig. 2, causing the valve *d* to be released from its seat, and thus allowing the water from the pipe *c* to be forced out all around the said valve, between it and 90 its seat, and thus causing the impurities to be removed from the said grooves or scratches *d' d'*. During such cleansing of the valve the dash-plate *G* is swung to the position shown in Fig. 2, so as to convey the waste water into 95 the conductor *H* and to the drain-pipe *h*.

The outer end of the valve *d* is forked or notched, as shown at *d''* in Fig. 5, for the purpose of receiving the lever *e*, and thus preventing said valve from turning around its 100 axis when being moved from and to its seat while being cleansed. In case the said valve

should become worn or damaged, it can easily be removed and a new one put in its place at a very small cost, or it may be regrooved, if so desired.

5 Having thus fully described the nature, construction, and operation of my invention, I wish to secure by Letters Patent, and claim—

1. The improved vaporizer consisting of the delivery-pipe *c*, having a tapering valve-seat *c'*, and longitudinally-grooved tapering valve *d d'*, combined with the pivoted dash-plate *G*, having inclined faces *G' G'*, substantially as and for the purpose set forth.

15 2. The improved vaporizer consisting of the delivery-pipe *c*, having a tapering valve-seat *c'*, and longitudinally-grooved tapering valve *d d'*, combined with the lever *e*, and spring *f*, for holding said valve against its seat, and the pivoted dash-plate *G*, having inclined 20 faces *G' G'*, substantially as and for the purpose set forth.

25 3. The improved vaporizer consisting of the delivery-pipe *c*, having a tapering valve-seat *c'*, and longitudinally-grooved valve *d d'*, and spring-pressed lever *e*, for holding said valve against its seat, combined with a pivoted

dash-plate *G*, having inclined sides *G' G'*, and the conductor *H*, substantially as and for the purpose set forth.

4. In a vaporizer, the delivery-pipe *c*, having tapering valve-seat *c'*, and spring-pressed and longitudinally-grooved valve *d d'*, combined with the pivoted dash-plate *G*, having inclined sides *G' G'*, and a stop-cock or cut-off on the supply-pipe, substantially as and 35 for the purpose set forth.

5. In a vaporizer, the delivery-pipe *c*, having tapering valve-seat *c'*, and spring-pressed and longitudinally-grooved valve *d d'*, combined with the pivoted dash-plate *G*, having 40 inclined sides *G' G'*, a stop-cock or cut-off on the supply-pipe, and a conductor *H*, having a drain-pipe *h*, substantially as and for the purpose set forth.

In testimony whereof I have signed my 45 name to this specification, in the presence of two subscribing witnesses, on this 8th day of March, A. D. 1890.

EDWIN W. PARKER.
